(57) **CLAIM**

The ornamental design for a bag, as shown and described.

DESCRIPTION

Such a bag is intended for use as a backpack.

FIG. 1 is a front perspective view of the bag of the present invention;

FIG. 2 is a front elevational view thereof;

FIG. 3 is a rear elevational view thereof;

FIG. 4 is a right side view thereof;

FIG. 5 is a left side view thereof;

FIG. 6 is a top view thereof; and,

FIG. 7 is a bottom view thereof.

The broken lines shown in FIGS. 1-3 of the views are understood to represent stitching.

1 Claim, 4 Drawing Sheets
